BRASSIÈRE

William Gluckin, New York, N. Y.

Application August 18, 1938, Serial No. 225,528

2 Claims. (CL. 2-42)

This invention relates to brassières, and the object of the invention is to provide a brassière having yieldably supported bust and side band portions so as to provide a garment of this type which might be termed universally adaptable to different body contours, while at the same time providing means for more firmly and comfortably supporting the breasts and for maintaining the breasts in the desired spaced relationship with respect to each other, a further object being to provide a brassière wherein the breast portions thereof are each composed of two suitable formed pieces of fabric, one piece of each breast part terminating in an extending strap portion having at its end an elastic coupling with the opposed side of the garment, and one of such strap ends and elastics being passed through and movable relatively to the other breast part so as to maintain the same relationship of the strap ends with respect to each other and to provide a brassière wherein the breast parts are free to move relatively to each other circumferentially of the body when arranged thereon, adjacent overlapping ends of the breast parts being independent of each other and slidably with respect to each other; a still further object being to provide a brassière wherein the side bands terminate at their rear ends in elastics having means for detachably coupling the same to provide a further yieldable mounting of the brassière upon the body of the wearer in producing the said universally adaptable characteristics of the garment, and with these and other objects in view, the invention consists in an article of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a front perspective view of the brassière made according to my invention with the several parts in a general arrangement which might be assumed if the garment were applied to the body of the wearer.

Fig. 2 is a section substantially on the line 2-2 of Fig. 1, and

Fig. 3 is a partial section on the line 3-3 of Fig. 1.

In the construction of brassières it has been more or less the conventional practice to couple or join the breast or bust portions thereof at the front central portion of the garment or inter-

mediate said breast receiving portions, and these couplings have been fixed as well as yieldable. It is one of the distinctive purposes of my invention to provide what may be termed totally free and independent breast receiving portions which are uncoupled or unattached at the intermediate sections thereof and are rather so constructed as to provide for a relative sliding movement of the breast parts one with respect to the other at the front or intermediate portion of the garment.

In the accompanying drawing I have shown one method of carrying my invention into effect, and as shown, the garment consists of a pair of breast parts 10 each composed of an upper fabric member 11 and a lower fabric member 12, stitched or otherwise secured together as indicated at 13 to provide the desired contour for said breast parts. The upper and lower members of the breast parts are joined at the sides of said garment, as indicated by the stitching 14, to substantially triangular side members 15, the upper edge 16 and the lower edge 17 of said members forming continuations of the upper edge 18 and the lower edge 19 respectively of said breast parts. The ends 20 of the side members 15 are joined to resilient straps 21 detachably joined by a suitable hook-shaped coupling 22.

The upper fabric members 11 of the breast parts terminate in tapered ends or strap members 23. The strap member of one breast part overlaps the strap member and the lower fabric member 12 of the second breast part, and the strap member of the second breast part passes through an opening 24 in the lower fabric member 12 of the first breast part. The ends 25 of the strap members 23 are secured to resilient straps 26, which in turn are secured to the lower portion of the opposed triangular side members 15 as indicated at 27 on the stitching lines 14.

Suitable shoulder straps 28 are provided for the garment and secured at the rear ends 29 thereof to the ends 20 of the side members 15. The front ends 30 of the straps 28 are secured to the upper portion 31 of the breast parts by yieldable straps 32, 32a. The ends 33, 33a of said straps are secured in spaced relation to the edge 18 of the upper breast members and provide by virtue of this spaced relation, form-fitting and form-retaining support. In practice the straps 32, 32a may comprise a single strap folded at the central portion thereof as indicated at 34.

The edges of the breast parts and the side members as well as the seam between the breast parts and side members are preferably finished with a bias strip in the conventional

manner as indicated at 35 in the various views, and the lower breast members 12 preferably have a lining of soft material as clearly seen at 36 in Figs. 2 and 3 of the drawing. It will of course be understood that the thickness of the various parts of the garment as shown in Figs. 2 and 3 is greatly exaggerated in order to facilitate a clear showing of the arrangement of parts, and that in the garment itself, the seams are relatively flat and in no way uncomfortable to the wearer.

It will be apparent that this improved brassière constitutes in reality two separate and independent breast supports combined in a single garment. In combination, the side members 15 together with the resilient strips 21 and the coupling 22 function as members of both breast supports, and each breast part is laterally supported by two resilient strips. For example, considering one side member as a fixed part of the garment with respect to the wearer, the opposed breast part is joined to the fixed side member by the resilient strips 21 and 26. Since this garment individually supports the breasts, it will be apparent that there will be no tendency for laterally crushing or spreading the breasts, but rather they will be maintained in their normal spaced relation while at the same time they will be given the desired upward support. In this connection it will be noted that the three-point resilient suspension of each breast part serves to provide true uplift properties.

It will further be noted that the overlapping portions of the parts 11 fit snugly upon the body 35 of the wearer intermediate the breasts, and that the straps 23 will bear upwardly against adjacent lower sides of the breast parts and operate to raise the same and to support the breasts in the raised position. The overlapping and 40 silently supported structure of the breast parts permit slight lateral movement of the breasts, thereby insuring greater comfort to the wearer of the garment without in any way decreasing the uplift and form molding properties thereof.

45 This provision of lateral movement of the breast parts also enables the manufacturer of garments of this type to materially decrease the number of different sizes, since a garment of one bust size will adapt itself to use by wearers having different bust measurements. From the manufacturer's standpoint, my improved brassière has other distinct advantages in that it is composed essentially of three pairs of cooperating parts which, when stitched together, provide the 55 form-fitting contour of the garment. The two

parts of each pair are of similar peripheral contour and can readily be fashioned from the structural material in a single operation. Likewise the various connecting straps 21, 26, 28 and 32 comprise duplicate members which can be fashioned 5 simultaneously. It will therefore be apparent that the garment is extremely simple and economical in construction.

While for purposes of illustration I have shown my garment as formed from plain or uncharacterized material, it will be understood that the structural features of this new brassière may be applied to more elaborate garments employing lace, and other conventional materials.

Having fully described my invention, what I 15 claim as new and desire to secure by Letters Patent, is:

1. In a brassière of the class described having side members terminating in rear straps detachably coupled for mounting the brassière upon the body of the wearer, two independent and relatively movable breast pockets, said pockets having outer sides fixedly secured to the side members of the brassière, adjacent end portions of said pockets having overlapped extensions terminating in reduced ends, said reduced ends extending onto the lower portions of opposed pockets, and elastic straps coupling the reduced ends with the side members to which opposed pockets are secured to provide free relative movement 30 of the pockets one with respect to the other circumferentially of the brassière.

2. In a brassière of the class described having side members terminating in rear straps detachably coupled for mounting the brassière upon the 35 body of the wearer, two independent and overlapped breast pockets, each of said pockets comprising upper and lower parts, the outer sides of both parts of each pocket being secured to the adjacent side member, the overlapped portions 40 of said breast pockets comprising tapered extensions of the upper parts only of said pockets, each of said extensions terminating in a reduced end arranged substantially centrally of the bottom part of the opposed breast pocket, the lower 45 part of one of said pockets having an aperture therein, the reduced end of the opposed pocket extension passing outwardly through said aperture, and elastic straps coupling the reduced ends with the side members to which the opposed 50 pockets are secured to provide free relative movement of the pockets one with respect to the other circumferentially of the brassière.
